US0D1034600S

(12) **United States Design Patent** (10) **Patent No.:** **US D1,034,600 S**
(45) **Date of Patent:** **** Jul. 9, 2024**

(54) **TOUCH PAD**

(71) Applicant: **Logitech Europe S.A.**, Lausanne (CH)

(72) Inventors: **Paul Benjamin Wolfson**, Lausanne (CH); **Maxence Frank Perret-Gentil**, Lausanne (CH)

(73) Assignee: **Logitech Europe S.A.**, Lausanne (CH)

(**) Term: **15 Years**

(21) Appl. No.: **29/844,537**

(22) Filed: **Jun. 29, 2022**

(51) **LOC (14) Cl.** **14-02**

(52) **U.S. Cl.**

USPC **D14/389**

(58) **Field of Classification Search**

USPC D14/126, 125, 300, 129, 132, 133, 239, D14/307, 371, 377, 366, 378, 379, 380, D14/381, 382, 399, 448, 496, 388, 389; D12/400, 192

CPC G06F 1/16; G06F 1/1601; G06F 1/1637; H05K 5/00; H04N 5/64

(57) **CLAIM**

The ornamental design for a touch pad, as shown and described.

DESCRIPTION

FIG. 1 is a front perspective view of the touch pad showing our new design;

FIG. 2 is a top perspective view thereof;

FIG. 3 is a bottom perspective view thereof;

FIG. 4 is a top plan view thereof;

FIG. 5 is a bottom plan view thereof;

FIG. 6 is a rear elevation view thereof;

FIG. 7 is a front elevation view thereof;

FIG. 8 is a left-side elevation view thereof; and,

FIG. 9 is a right-side elevation view thereof.

The broken lines shown in the figures show unclaimed features of the touch pad and form no part of the claimed design.

1 Claim, 6 Drawing Sheets
